UNITED STATES PATENT OFFICE.

WILLIAM C. CARTER, OF ST. LOUIS, MISSOURI, ASSIGNOR TO CARTER CARBURETOR COMPANY, OF ST. LOUIS, MISSOURI, A CORPORATION OF MISSOURI.

CARBURETER.

1,169,616.

Specification of Letters Patent. Patented Jan. 25, 1916.

Application filed February 3, 1913. Serial No. 745,949.

To all whom it may concern:

Be it known that I, WILLIAM C. CARTER, a citizen of the United States, residing at St. Louis, Missouri, have invented a certain new and useful Improvement in Carbureters, of which the following is a full, clear, and exact description, such as will enable others skilled in the art to which it appertains to make and use the same.

10 This invention relates to carbureters, and has for its main object to provide a carbureter of novel design which is so constructed that a starting charge of rich combustible gas will be supplied to the cylinders 15 of the motor when the motor is cranked or started.

Another object is to provide a carbureter of the kind just described which comprises means under control of the operator for cutting off the supply of liquid fuel or raw fuel 20 from which the said starting charge is produced after the motor has started.

Another object is to provide a carbureter which is so designed that the mixture which 25 is supplied to the cylinders of the motor when the motor is throttled down or first started will be introduced into the intake manifold in such a manner that the fuel and air constituting said mixture will become 30 thoroughly mixed before entering the cylinders, thus insuring charges of equal richness to all the cylinders of the motor. And still another object is to provide a carbureter that comprises a passageway whose upper 35 end terminates at a point between the throttle valve and the cylinders of the motor and whose lower end communicates with a supply of raw fuel or unvaporized fuel, means for supplying air to said passageway, 40 and a valve for controlling said passageway, said valve being preferably so designed that it can be turned so as to cut off the supply of raw fuel to said passageway without cutting off the flow of air through said passageway.

Other objects and desirable features of my invention will be hereinafter pointed out.

I have herein illustrated my present invention embodied in a carbureter of the type 50 shown in my prior Patent #1,040,619, dated October 8, 1912, but I do not wish it to be understood that the invention is limited to a carbureter of the type mentioned as it is applicable to various types of carbureters.

Figure 1 of the drawings is a side elevational view of a carbureter embodying my present invention; Fig. 2 is a vertical longitudinal sectional view of the carbureter shown in Fig. 1; Fig. 3 is a detail vertical 60 sectional view taken on the line 3—3 of Fig. 1 showing the starting valve open; Fig. 4 is a similar view showing the starting valve closed; Fig. 5 is a vertical sectional view taken on the line 5—5 of Fig. 3; and Fig. 6 65 is a vertical sectional view taken on the line 6—6 of Fig. 4.

Referring to Fig. 2 of the drawings which illustrates the preferred form of my invention, A designates the float chamber, B designates the mixing chamber, and C designates the throttle-valve that controls the passage of the mixture from the mixing chamber into the intake-pipe of the motor. The liquid fuel passes from the float chamber through a duct 1 into the lower end of a vertically disposed jet tube D that is arranged inside of an air-pipe E through which air is drawn into the mixing chamber as clearly described in my prior patent previously referred to, said jet tube being provided with a plurality of fine jets or orifices through which the liquid fuel escapes from the jet tube in the form of a fine spray that is vaporized by the air that passes down 75 through the air-pipe E.

In order that a charge of rich combustible gas will be supplied to the motor when the motor is cranked, thus causing the motor to start easily, I have equipped the carbureter 80 with a passageway that leads from a supply of liquid fuel or raw fuel to a point above the throttle-valve and have provided means for admitting air to said passageway so as to convert the raw fuel into a combustible mixture.

In the embodiment of my invention illustrated a small pipe or conduit 2, which is arranged inside of the mixing chamber B, communicates at its upper end with the intake pipe F at a point above the throttle-valve, and at its lower end with a valve casing 3, see Figs. 3 and 4, in which an oscillating valve G is mounted. A small pipe or conduit 4, preferably of the same cross-sectional area as the pipe 2, leads from the valve casing 3 to the duct 1 that establishes communication between the float chamber A and the jet tube. The valve G is provided with a fuel port 6 that establishes direct communication between the two 100

95

100

105

110

- conduits 2 and 4 when the valve G is open, as shown in Fig. 5, thus permitting the raw fuel to be drawn up through said conduits 4 and 2 into the intake-pipe F of the motor. Said valve G is also provided with a longitudinally disposed air duct 7 that branches laterally from the fuel port 6 in said valve, the outer end of the air duct 7 being open, as shown in Fig. 3, so that air can pass from 10 the mixing chamber into the duct or pipe 2 and convert the raw fuel that is sucked upwardly through said pipe into a combustible mixture. The valve G is provided with an arm 8 so that it can be turned into the 15 position shown in Fig. 5 when the operator desires to start the motor, and after the motor has started said valve can be turned into the position shown in Fig. 6 so as to cut off the supply of raw fuel to the duct 2 that 20 terminates above the throttle-valve. In order to insure sufficient suction in the mixing chamber, when the motor is throttled down, to cause the air to travel through said chamber quickly enough to prevent the 25 liquid fuel supplied by the jet tube from becoming deposited on the walls of the mixing chamber, I have provided the valve G with an air port 9 that establishes communication between the air duct 7 in the valve 30 and the pipe 2, when the valve is closed, as shown in Fig. 6.
- From the foregoing it will be seen that air is supplied to the passageway through which the raw fuel is drawn when the valve G is 35 closed, as shown in Figs. 4 and 6, no raw fuel or liquid fuel will be supplied to the pipe 2 by the pipe 4 that communicates with the supply of liquid fuel. To eliminate the possibility of liquid fuel escaping from the supply pipe 4 and leaking around the valve G into the duct 2 when said valve is closed, I have formed a small groove 10 in the outer surface of the valve G that 40 establishes communication between the fuel supply pipe 4 and the atmosphere when the valve G is closed, said groove 10 leading from the pipe 4 to a point on the outside of the carbureter, as shown in Fig. 4. In 45 other words, the valve G is provided with an air groove 10 which supplies air to the raw fuel supply pipe 4 when said valve is closed so as to prevent the raw fuel from being drawn up into the pipe 2 either by a 50 siphonic action or by suction resulting from a leak around the valve. Any suitable means may be used for holding the valve G in its open and closed positions, the means herein shown consisting of a spring-actuated 55 plunger 11 mounted in a housing 12 on the exterior of the carbureter and adapted to co-operate with notches or recesses 13 in the upper end of the valve arm 8, as shown in Fig. 1.
- 60 While I prefer to form the carbureter in

the manner previously described it will, of course, be understood that various changes could be made without departing from the spirit of my invention which, broadly stated, consists in a carbureter having a passageway leading from a supply of raw fuel to a point between the throttle-valve and the cylinders of the motor, means for admitting air to said passageway so as to vaporize the fuel flowing through same and thus produce a rich combustible gas, and a valve or other suitable device for cutting off the supply of raw fuel to said passageway after the motor has started.

As previously stated, one of the objects of my present invention is to provide a carbureter which is so designed that the mixture which is supplied to the cylinders when the motor is throttled down or first started will be introduced into the intake manifold 70 in such a manner that the fuel and air constituting the mixture will become thoroughly mixed before entering the cylinders, thus insuring a charge of equal richness to all of the cylinders of the motor. I accomplish this desirable result by introducing the mixture from the pipe 2 tangentially into the intake-pipe F so that it will travel upwardly through the intake-pipe with a circular or whirling action. As shown in Fig. 2, the upper end of the pipe 2 communicates with an annular chamber 14 that surrounds the passageway which the throttle-valve controls, and said chamber 14 is provided with one or more discharge ports 15 that are tangentially disposed. Consequently the mixture that escapes from said duct or ducts 15 will enter the intake-pipe F at a tangent and will whirl upwardly through said pipe in a circular path. This prevents some of the 80 cylinders of the motor from receiving an exceedingly rich mixture and the other cylinders receiving a lean mixture for the upward whirling action causes the fuel and air to be thoroughly mixed in such a manner that there is no tendency for the air to take one path and flow into some of the cylinders and the fuel to take a different path and enter different cylinders. It is, of course, not necessary that the upper 90 end of the pipe 2 terminate in an annular chamber 14 as herein shown, for, if desired, the pipe 2 could lead directly to the passageway which the throttle-valve C controls but I prefer to form the carbureter in the manner herein shown on account of the fact that it permits the mixture from the pipe 2 to be introduced into the intake-pipe at several different points. Furthermore 100 while it is preferable to introduce said mixture into the intake-pipe tangentially, this is not essential to the successful operation of my carbureter.

A carbureter of the construction above-described insures easy starting of the motor

- on which it is used owing to the fact that a rich mixture of fuel and air is supplied directly into the intake-pipe at a point above the throttle-valve when the starting valve G 5 is open. Furthermore, there is no liability of the mixing chamber loading up with an exceedingly rich mixture when the motor is throttled down because the pipe 2 which always remains open, irrespective of whether 10 the starting valve G is open or closed, insures sufficient suction in the mixing chamber to prevent the liquid fuel from collecting on the walls of the mixing chamber. In addition to the desirable features above-mentioned, my improved carbureter insures a 15 uniform mixture to all of the cylinders of the motor when the motor is throttled down or is being started on account of the fact that the mixture is introduced into the intake-pipe in such a manner that it will whirl upwardly through the intake-pipe in a circular path, thereby causing the air and fuel to mix thoroughly before they reach the cylinders. 20
- 25 The needle-valve that controls the supply of liquid fuel to the float chamber is so constructed that vibration of the motor will not cause said valve to unseat or jump up and down and thus admit too much fuel to the 30 float chamber. As shown in Fig. 2, the needle-valve 16 that controls the supply of liquid fuel to the float chamber A is loosely mounted in the stem or member 17 that bears on the lever 18 with which the float 35 19 in the float chamber coöperates. A pin 20 in the stem 17 that projects into an elongated slot 21 in the shank of the valve 16, causes said valve to move upwardly off of its seat when the float 19 exerts sufficient downward pressure on the lever 18 to raise the member 17 in which the valve 16 is loosely mounted, and a coiled expansion spring 22 which is arranged in a bore in the member 17 exerts sufficient pressure on the shank of 40 the valve to normally hold the pin 20 at the upper end of the slot 21. The spring 22 normally holds the valve seated and thus reduces the tendency of the valve to jump up and down due to vibration of the motor, 45 said spring acting as a cushion between the valve and the member 17 so that said member 17 will remain at rest even if the valve is moved upwardly slightly by an abnormal vibration or shock. Consequently, a valve 50 55 of the construction above-described insures a uniform level of fuel in the float chamber, thereby effecting a great saving in the quantity of liquid fuel used.
- Having thus described my invention, what 60 I claim as new and desire to secure by Letters Patent is:
1. A carbureter provided with a passageway that leads from a supply of raw fuel to a point above the throttle valve, means for 65 supplying air to said passageway so as to convert the fuel in same into a combustible mixture, and means for cutting off the flow of raw fuel through said passageway and for establishing communication between said passageway and the mixing chamber of the carbureter after the motor has started to run properly. 70
  2. A carbureter provided with a main suction passageway and a throttle valve for controlling the flow of the mixture through said passageway to the engine, a duct that leads from a supply of liquid fuel to a point above said throttle valve, means for admitting air to said duct at a point above the place where the liquid fuel enters same so as to convert the fuel in same into a combustible mixture, and means for stopping the flow of liquid fuel through said duct without interrupting the flow of air through said duct. 75
  3. A carbureter provided with a passageway that leads around the throttle valve and establishes communication between the mixing chamber and the intake pipe of the motor, means for supplying raw fuel to said passageway so as to produce a rich starting charge of fuel and air, and means that is adapted to be actuated after the motor is running properly for cutting off the supply of raw fuel to said passageway. 80
  4. A carbureter provided with a duct leading from the mixing chamber to a point above the throttle valve for insuring sufficient suction in the mixing chamber when the motor is throttled down to prevent the liquid fuel from collecting in the mixing chamber, and manually operated means under control of the operator for enabling a rich combustible mixture of raw fuel and air to be supplied to the motor through said duct to facilitate easy starting, and for positively cutting off the supply of liquid fuel to said duct after the motor has gained headway. 85
  5. A carbureter provided with a passageway that leads from a supply of raw fuel to a point above the throttle-valve, and means for cutting off the flow of raw fuel through one part of said passageway without interfering with the flow of air through the remaining part of said passageway after the motor is running properly. 90
  6. A carbureter provided with a duct whose upper end communicates with the intake-pipe between the throttle-valve and the cylinders of the motor and whose lower end communicates with the mixing chamber, and a manually controlled means for governing the admission of raw fuel to said duct. 100
  7. A carbureter provided with a passageway that leads from a supply of raw fuel to a point above the throttle-valve, a cut-off valve arranged intermediate the ends of said passageway for cutting off the flow of raw 105

fuel through said passageway, means for admitting air to said passageway irrespective of the position of the valve, and a fuel duct in said valve which permits the raw fuel to flow through said passageway only when the valve is in a certain position.

8. A carbureter provided with a passageway that leads from a supply of raw fuel to a point above the throttle-valve, a valve arranged intermediate the ends of said passageway, means for admitting air to said passageway irrespective of the position of the valve, a fuel duct in said valve which permits the raw fuel to flow through said passageway only when the valve is in a certain position, and means for preventing the raw fuel from leaking around the valve and thus being sucked up into the upper portion of said passageway when the valve is closed.

9. A carbureter provided with a passageway that leads from a supply of raw fuel to a point above the throttle-valve, a valve arranged intermediate the ends of said passageway for cutting off the flow of fuel through said passageway, means for admitting air to said passageway irrespective of the position of the valve, and a fuel duct in said valve which permits the raw fuel to flow through said passageway only when the valve is in a certain position, said valve being provided with means which establishes communication between the atmosphere and one portion of said passageway when the valve is closed, thereby preventing the raw fuel from leaking around said valve into the upper portion of said passageway.

10. A carbureter provided with a passageway that leads from a supply of raw fuel to a point between the throttle-valve and the

cylinders of the motor on which the carbureter is used, a valve arranged intermediate the ends of said passageway for cutting off the flow of the raw fuel through said passageway, and means in said valve that establishes communication between the mixing chamber of the carbureter and the upper portion of said passageway at all times, irrespective of the position of the valve.

11. A carbureter provided with a mixing chamber, a valve casing in the wall of said chamber, a duct leading from said casing to a point above the throttle-valve, a duct leading from said casing to a supply of raw fuel, a valve in said casing provided with a fuel port that alines with said ducts when the valve is in a certain position, and means in said valve that establishes communication between the mixing chamber and the duct that leads to a point above the throttle-valve.

12. A carbureter provided with a mixing chamber, a multiple jet tube for supplying fuel to said chamber, an air-pipe surrounding said jet tube for causing air to travel down around same into the mixing chamber, and means whereby a rich mixture of fuel and air can be supplied the intake-pipe of the motor at a point above the throttle-valve when the motor is started, and thereafter cut off from said intake-pipe after the motor is running properly.

In testimony whereof I hereunto affix my signature in the presence of two witnesses, this thirty-first day of January, 1913.

WILLIAM C. CARTER.
